UNITED STATES PATENT OFFICE.

EDWARD A. COLBY, OF NEWARK, NEW JERSEY.

ELECTRIC ILLUMINATING APPARATUS.

SPECIFICATION forming part of Letters Patent No. 499,097, dated June 6, 1893.

Application filed February 15, 1893. Serial No. 462,406. (No model.)

To all whom it may concern:

Be it known that I, EDWARD A. COLBY, of Newark, Essex county, New Jersey, have invented a new and useful Improvement in 5 Electric Illuminating Apparatus, of which the following is a specification.

My invention relates to an electric incandescent or glow lamp in annular form and containing a filament in the form of a ring or 10 closed coil. The said filament has no leading-in wires, and is rendered incandescent by induction by being disposed in a varying field such as is produced by an alternating, pulsating, or intermittent current.

15 My invention consists more particularly in the construction of the annular glow lamp: the combination of two or more of said lamps with an inducing coil: the construction and arrangement of the lamp support: and the 20 providing of the same with reflecting surfaces, and in the construction of a novel arrangement of annular lamps, coils and supporting body which I term a "rope of light" and by means of which entirely new and striking 25 effects in electrical illumination may be produced.

In the accompanying drawings, Figure 1 is a sectional, and Fig. 2 is a plan, view of my annular lamp. Fig. 3 is a vertical section 30 showing the construction of the inducing coil and support and the disposition of two or more lamps thereon. Fig. 4 illustrates the construction of my so-called "rope of light;" several series of lamps and inducing coils 35 being disposed upon a flexible iron wire cable. Fig. 5 shows said "rope of light" bent to form letters for illuminated signs or signals. Fig. 6 shows said rope wound or coiled about a support to produce apparently a solid 40 mass of incandescent matter, and Fig. 7 shows said rope laid in a flat coil, so as to render luminous large surface areas.

Similar letters of reference indicate like parts.

45 The lamp consists of a glass tube, A, Figs. 1 and 2, which may be made in elliptical, or as is here shown, in circular, form. Within this tube is placed the carbon filament B of any material suitable for the filament in an 50 incandescent or glow lamp, which filament is held in place in the tube by means of supports, C, of platinum wire, which are sealed

into the material of the tube. The wires C are not leading-in wires for any current; the circular filament B being completely inclosed 55 and insulated within the tube A. I propose to cause the filament B to glow and become incandescent by placing the lamp in a varying field of force, as, for example, in such relation to a transformer or induction coil as that 60 the circular filament B shall be the secondary coil thereof, and thus be caused to glow by the induced current set up therein due to its location in the field of the primary coil. In Fig. 3 is shown a convenient arrangement for this 65 purpose. Here G is a primary coil connected by wires I J with any suitable source of varying (alternating, pulsating or intermittent) current. H is the core of said primary coil, preferably made of a bundle of straight wires. 70 The core H protrudes beyond the primary coil, as G. In order to bring my lamp A into operation, I have simply to place it upon the core H, as shown in Fig. 3, when the filament B, being in inductive proximity to the coil G, 75 will be caused to glow. Where it is desired to increase the intensity of the light, I may multiply lamps, A, upon the core H, as shown at A', A'', &c.; one lamp simply resting upon the other. Or, by still farther prolonging the 80 core H and placing thereon several primary coils, as G, G', G'', and numerous interposed lamps, as A, A', &c., as shown in Fig. 4, I may produce a continuous bar, so to speak, of lamps. In this way I may produce an illuminating source of indefinite length, and by 85 making the core H flexible (as, for example, of wire rope), entirely novel and striking effects in electrical illumination may be obtained. Thus, I may carry my "rope of light" 90 entirely around a room like a molding or cornice; or, I may twist or bend it into ornamental designs, such as letters, as shown in Fig. 5, so that in this way I may produce illuminated signs or inscriptions. As the flexibility 95 of the rope allows of a single length being easily and quickly changed in form, I propose to use the letters or inscriptions thus formed for night signaling between distant points, or for advertising purposes. By coiling the "rope of light" closely around any suitable support, as shown in Fig. 6, I may produce pillars or blocks of almost any size and apparently from a little distance, an in-

candescent mass; or by placing the "rope" in a flat coil, as shown in Fig. 7, I may render large areas brilliantly glowing.

As shown in Fig. 4, the coils G G', &c., may be electrically connected. In order to support the annular lamps A A' on the core H when the same stands vertically, I provide on said core a threaded sleeve, K, upon which the lamps loosely fit. A nut, L, upon said sleeve then supports the lamps from below and also allows of their adjustment in any desired position. I propose to make all surfaces of the support which are covered by the lamps, bright or light reflecting. This I may do by silver or nickel plating, by the interposition of mirrors, or in any other suitable way. In the device shown in Fig. 4, the entire periphery of the core H would thus be made bright.

In the foregoing, I have described the filament as made wholly of carbon or other material intended to glow or incandesce in the lamp, but it is to be understood that I do not limit myself to a filament thus constructed. Thus, I may make the filament partly of a body of high resistance which glows or incandesces and partly of a body of lower resistance, as, for example, a wire of platinum or other suitable material. In Fig. 2, for example, the filament may be regarded as made in three sections marked by the positions of the supports C. I may make one or two of these sections of platinum wire and the remaining two or one of carbon; the carbon portion only incandescing. In this way I can produce the greatest expenditure of energy in a fractional portion only of the whole filament with corresponding increase of brilliancy. This construction is preferable in cases where the lamp is placed on one side against an opaque body or support, as in Figs. 5, 6 and 7; the external part of the filament then only glowing.

I claim—

- 45 1. In an electric illuminating apparatus, a primary coil, a support, and two or more independent glow lamp receivers on said support, each receiver containing a filament in ring or closed coil form: the aforesaid parts being constructed and arranged so that said filaments shall each become a secondary to said primary coil and be caused to glow by the induced current, substantially as described.
- 55 2. In an electric illuminating apparatus, a support, a means of producing a variable field of force combined therewith, two or more glow lamp receivers adapted to be held upon said support, each receiver inclosing within it, a filament in ring or closed coil form: the aforesaid parts being constructed and arranged so that when said receivers are held upon said supports said filaments shall be in said variable field, substantially as described.
- 65 3. In combination with an electric glow lamp having an annular receiver and a fila-

ment in ring or closed form concentric therewith and inclosed therein, an elongated body of inductive material entering the cylindrical space surrounded by said receiver and a coil 70 upon said body, substantially as described.

4. In an electric illuminating apparatus, an elongated body of inductive material, and received thereon a coil and two or more glow lamps each having an annular receiver, and 75 a filament in ring or closed coil form therein, substantially as described.

5. In an electric illuminating apparatus, an elongated body of inductive material and received thereon a coil, two or more glow lamps 80 each having an annular receiver and a filament in ring or closed coil form therein, and means for preventing lateral motion of said lamps upon said body, substantially as described.

6. In an electric glow lamp, a receiver in the form of an annular tube, and a ring or closed coil filament without leading in wires disposed and supported in the axial line of said tube, substantially as described.

7. As a new article of manufacture, an elongated body of inductive material, a series of inducing coils thereon, and a series of annular electric glow lamps also thereon each lamp having a filament in ring or annular form, 95 substantially as described.

8. As a new article of manufacture, a flexible elongated body of inductive material (such as wire rope), a series of inducing coils thereon and a series of annular electric glow lamps 100 also thereon, substantially as described.

9. The combination of a coil, a core depending therefrom, two or more electric annular glow lamps received upon said core and means for adjusting said lamps simultaneously in 105 position along said core, substantially as described.

10. The combination in an electric glow lamp of the annular receiver, a ring filament therein without leading in wires and supports 110 for said filament, substantially as described.

11. The combination of the threaded core K, coil G, annular electric glow lamps A, A', &c., and nut L on said core, substantially as described.

12. The combination of the threaded core K, coil G, annular electric glow lamps A, A', &c., nut L and shade M, substantially as described.

13. In an annular or hollow cylindrical electric glow lamp a filament in ring or closed coil form constructed of two bodies of different resistances, substantially as described.

14. In an annular or hollow cylindrical electric glow lamp, a filament of carbon having 125 an inserted section of metal, substantially as described.
